UNITED STATES PATENT OFFICE

VICTOR H. HARBERT, OF CHICAGO, ILLINOIS, ASSIGNOR TO ILLINOIS RAILWAY EQUIPMENT COMPANY, OF CHICAGO, ILLINOIS, A CORPORATION OF ILLINOIS

LOCKING MEANS

Application filed July 13, 1931. Serial No. 550,393.

My invention relates to means especially intended for fastening or locking the hatch covers of railroad refrigerator cars, either in closed position or in a predetermined ventitating position.

The invention has for its object the provision of means so secured or associated with a swinging member or lever arranged adjacent to the hatch that said means may be readily moved along the lever and be positioned for locking the hatch cover in closed position or lock the cover in a predetermined raised position for ventilation; the relation between the lever and locking means being such that dissociation of the elements is impossible; while at the same time said means are so constructed and arranged that engagement with the running boards or with portions of the car-roof is impossible.

The objects and advantages of my invention will be readily comprehended from the following detailed description of the accompanying drawing, wherein:

Figure 1 is a plan view of a portion of car-roof with a hatch cover in closed position, illustrating my improved means in cover locking position.

Figure 2 is a transverse sectional view with the locking means in side elevation; a ventitating position of the cover being shown in dotted lines.

Figure 3 is a perspective view of the locking means unattached.

Locking means as heretofore employed consisted of a hook secured to the hatch cover by means of a chain and the hook intended to pass through a suitable staple on the car-roof which cooperated with a hasp member secured to the hatch cover. This type of fastening means has been found to be very objectionable because the hooks were free to become engaged with the running boards on the car-roof when in unlocked condition because the chains permitted the hooks to shift or be moved along the roof and also to swing

into the hatch opening when the cover is being moved to closed position. As a result, considerable damage and loss of the hooks has been encountered when the heavy hatch covers were swung and dropped into closed position.

My improved means is designed to overcome these serious objections and to provide means which may be readily secured to equipment in use.

The specific embodiment of my invention as disclosed in the drawing involves a member or shoe 10 which is adapted to be slidably mounted on a link or bar 11 whose one end is pivotally secured at 12 to an upstanding bracket member 13. The bracket member 13, for purposes of exemplification, is shown in the nature of an L-shape bar, one leg or side whereof is intended to be secured to the car-roof as by means of the bolts 14, 14, see Figure 1; while the other leg or side extends vertically upward. This bracket 13 is secured to the car-roof adjacent to the hatch 15 so as to be slightly spaced from the free end of the hatch cover 16, whose opposite end is hingedly secured in place, as shown at 17, 17.

The link or bar 11 is pivoted to the bracket 13 so as to swing over and into substantially parallel relation with the cover 16 when the latter is in closed position, as shown in full lines in Figures 1 and 2; and this link or bar is preferably provided with a number of openings or slots 18, spaced apart lengthwise of the link 11.

The member or shoe 10 is shown provided with two side wall portions 19, 19, which extend above and below the intermediate body portion or web 20, which is of length substantially equal to the width of the link or bar 11 so as to permit the latter to extend between the depending portions of the sides 19, 19. The lower ends of the sides 19, 19 are shown provided with the inwardly disposed flanges 21, 21.

These opposingly arranged flanges 21, 21 are spaced from each other a distance less than the width of the link or bar 11; and are spaced from the body portion or web 20 just sufficient to accommodate the thickness of the link or bar 11 so as to permit the member or shoe 10 to freely slide lengthwise of the link or bar, but without undue play therebetween.

The portions of the sides 19, 19, disposed above the body portion or web 20, are provided with aligned openings or holes at 22, generally corresponding in configuration with the cross-sectional configuration of the locking member or pin 23, so as to permit lengthwise sliding movement of the pin 23.

The pin 23 is in the nature of a U-shape hook with one leg or side 24 of greater length than the other side; and this side 24, at its end, is provided with a laterally disposed lug or enlargement as at 25.

One side of each opening 22, in the up-standing side portions of shoe 10, is provided with a laterally disposed enlargement or slot 26, intended to correspond in shape with the shape of the enlargement or lug 25 on the end of the pin 23.

The slot portions 26 and the lug 25 are arranged to be out of register with each other when the pin 23 is in normal assembled relation with the shoe or pin holder 10; and therefore, in the drawing, the lug 25 and the slots 26, 26 are shown ninety degrees apart relative to the axis of the long leg or side 24 of the locking pin 23; with the distance between the lug 25 and the adjacent side 19 of the shoe 10 less than the length of the short leg or side 27 of the locking pin 23.

As a result of this arrangement, the long leg 24 of pin 23 must first be inserted through the openings 22 in the sides 19 of the shoe 10 by turning or holding the short leg 27 downwardly so as to bring the lug 25 into register with the slots 26; the short leg or side 27 is then swung upwardly into the position shown in Figure 3 and the free end of the link or bar 11 is then passed transversely through the shoe 10 intermediate of the body portion 20 and the inturned flanges or bottom extensions 21, 21, with the short leg or side 27 of the pin 23 resting on top of the link or bar 11.

With the short leg or side 27 resting on top of the link or bar 11 as described, the lug 25 on the long leg or side 24 of the pin will be disposed as shown in Figure 3 and therefore out of register with the slots 26, 26. As the distance between the lug 25 and the adjacent side 19 of the shoe 10 is less than the length of the short leg or side 27 of the pin 23, it is apparent that the end of the short leg 27 will at all times rest on top of the link or bar 11, thus making it impossible to bring the lug 25 into register with the slots 26, 26 and hence dissociation of the locking means will be prevented.

After the locking means has been assembled as described with the shoe slid onto the link or bar 11, the free end of the latter is then provided with a rivet as at 28 which prevents the shoe 10 sliding off the free end of the bar 11.

The hatch cover 16 at a proper distance from its free end is provided with a suitable staple 29 which is intended to pass through one of the slots 18 in the bar 11 when the cover is in closed position, as shown in Figures 1 and 2; and this staple 29 is intended to receive the short leg 27 of the pin 23, thereby holding the link or bar 11 in substantially parallel relation with the hatch cover 16, as shown, and latching the cover in place.

The short leg 27 and the long leg 24 are provided with registering openings or slots 30, 30 which are adapted to receive the usual car sealing element in the nature of a wire or metal strip, indicated at 31 in Figure 1; the wire or strip being passed through both slots and the ends sealed together with solder or other suitable sealing medium, as indicated at 31a in Figure 1. Movement of the short side or leg 27 out of the staple 29, without first breaking and removing the seal, is thus prevented.

In order to prevent too far transverse movement of the pin 23 that the slot 30 of leg 24 would be disposed within the opening 22 of the side wall of shoe 10, I prefer to provide the leg 24 at the inner or hook end with a lug 32, see Figure 3, extending in the same direction as lug 25 so that lug 32 will be out of register with the slot portion 26 of the opening 22 in the side wall 19 of the shoe 10 and thus provide a stop for limiting the inward movement of the pin toward locking position, as shown in Figure 3.

In order to permit the hatch cover 16 to be held in car ventilating position, I show the cover 16 provided with a hasp or strap 33 whose end extends beyond the free end of the hatch cover as shown in Figure 2, and the strap provided with a suitable aperture 34 extending horizontally therethrough.

The strap 33 may be an integral part of the staple portion 29; and this strap is suitably secured to the cover 16.

The extended end of the strap 33 is intended to fit into any one of the slots 18 in the link or bar 11, as shown in dotted lines 120 in Figure 2; and this adjusted position of the elements is maintained by sliding the shoe 10 along the link or bar so as to position it adjacent to the strap 33 and then passing the short leg 27 of the hook-pin 23 through hole 34 of strap 33. When necessary, the means may be sealed in this position by employing the usual sealing means as heretofore described.

Providing the link or bar 11 with a num- 130

ber of holes or slots 18, enables the cover to be secured in the desired open position.

As is apparent from the drawing, my improved locking pin or hook member is always maintained in position where the short leg can be readily slid through the eye of the staple 29 or the eye of the strap 33; while dissociation of the link or bar and the locking means is impossible.

10 I have shown what is believed to be the simplest embodiment of the invention and have described it in terms employed merely for purposes of description and not as terms of limitation, as modifications may be made 15 without, however, departing from the spirit of my invention.

What I claim is:

1. Locking means of the character described comprising, in combination with a 20 hatch cover, a bar pivoted at one end and adapted to swing across the hatch cover; a channeled member formed to permit the bar to be endwise slid through the channel and permit the member to slide lengthwise of the bar, and a U-shaped locking pin slidably mounted in the upper part of said member so as to move in a direction transversely of the bar, the two legs of the pin being formed to receive a sealing medium.

20 2. Locking means of the character described comprising, in combination with a hatch cover provided with an upstanding staple and a staple at one end thereof, a bar pivotally mounted at one end so as to swing 25 vertically across the cover and provided with spaced apart openings adapted to receive either of said staples, a member loosely mounted on said bar to slide lengthwise thereof, and a U-shaped locking pin carried in the upper 30 part of said member and adapted to slide transversely thereof so as to permit one leg of the pin to pass through the upstanding staple when the bar is disposed across the top of the cover or through the end staple when 35 the cover and bar are in raised position, said 40 pin being formed to prevent its removal from said member and to receive a sealing medium.

3. Locking means of the character described comprising, in combination with a 40 hatch cover provided with an upstanding staple and a horizontally disposed staple at the free end, a bar pivotally mounted at one end so as to swing vertically across the cover and provided with a plurality of openings, 45 adapted to receive either one of said staples, a member slidably mounted on said lever, and a pin mounted in said member so as to slide transversely of the bar, the ends of the pin being formed to prevent removal of the 55 pin from the member and provided with a sealing medium receiving opening.

4. Locking means of the character described comprising a bar pivoted at one end so as to swing vertically, a block provided 60 with a passage adapted to endwisely receive

said bar and permit the block to slide lengthwise of the bar, means at the free end of the bar to prevent removal of the block, a U- 70 shape pin slidably mounted in said block so as to permit movement of the pin transversely of the bar, said pin being formed with a sealing medium receiving portion, and means whereby withdrawal of the pin from said block is prevented.
